MEANS FOR SLITTING AND RE-COILING
STRIP METAL

Eo Reed, Zanesville, and Donald H. Washburn,
Middletown, Ohio, assignors to The American
Rolling Mill Company, Middletown, Ohio, a
corporation of Ohio

Application October 19, 1942, Serial No. 462,582

10 Claims. (Cl. 164—65)

The slitting and recoiling of strip metal has proved a matter of considerable general difficulty in steel mills and metal manufacturing plants. We intend the term "slitting" to be a comprehensive one, including all procedures of longitudinally cutting strip metal, ranging from the mere decoiling, edge trimming and recoiling of strip to the severance of strip into a plurality of narrower strips, and the recoiling of these narrower strips into individual coils. Even where the initial strip is formed as such by the more modern processes of continuous rolling, difficulty is encountered in slitting and recoiling due to a number of factors, including the "crown" or variation in the thickness of the strip in the direction of its width. In slitting and recoiling very thin strip materials, there is always difficulty in properly guiding them because of the tendency of side guides to damage the edges of the material. Special materials present additional special problems. For example, there is a practice of producing silicon steel strip by hot rolling silicon steel sheets to thin gauge, and welding these sheets together end to end by special procedures outlined in Patents Nos. 2,172,080, 2,172,081, 2,219,493, 2,175,615, 2,175,616, 2,196,941, 2,282,611 and 2,254,314. The resultant welded material is very thin, frequently quite brittle due to the nature of the silicon steel alloy, and characterized by pronounced lack of flatness. These difficulties are so great that special precautions have had to be taken in the past even to coil the material, and it has been the practice to form a coil on a vertical mandrel having a lower horizontal flange upon which the coil rests, and to endeavor to make a fairly uniform and tight coil by periodically but not continuously retarding the strip so as to tension it during the rotation of the mandrel.

The principal objects of our invention are the provision of a mode of treatment and an apparatus whereby strip material may be slit and recoiled with an avoidance of the hitherto experienced difficulties, even in the case of such materials as present exaggerated difficulties, like the thin welded silicon steel strip to which reference has been made. Ancillary objects of our invention will be better understood in connection with the specific description which follows, and wherein they will either be pointed out or will be apparent to the skilled worker in the art. We accomplish the objects of our invention by the procedure and mechanism of which we shall set forth an exemplary embodiment.

Reference is made to the drawings wherein:

- Figure 1 is an elevational view of an exemplary mechanism assembly with certain parts in section.
- Figure 2 is a sectional view through a tensioning device of a preferred form.
- 5 Figure 3 is a transverse sectional view thereof taken along the line 3—3 in Figure 2.
- Figure 4 is an elevational view of a modified form of tensioning means.
- 10 Figure 5 is a sectional view taken along the line 5—5 of Figure 4.
- Figure 6 is a view similar to that embodied in Figure 5, excepting that the belt arrangements are shown open.
- 15 Figure 7 is a plan view of a guide means which may be employed in connection with the mechanism of Figure 6, and is a view taken in the direction 7 shown in that figure.
- Figure 8 is a plan view of a so-called chain guide, with parts broken away.
- 20 Figure 9 is an elevational view thereof.
- Figure 10 is a sectional view taken along the line 10—10 in Figure 9.
- Figure 11 is a partial assembly elevation (with parts in section) showing a slitting mechanism set up to divide a wide strip into a plurality of narrow strips, together with the tensioning means and a recoiler.
- 25 Figure 12 is a plan view of guide means employed in connection with the mechanism of Figure 11, and related to the direction 12 in that figure.
- Figure 13 is a view of the same arrangement, taken along the line 13—13 in Figure 12.
- 30 Figure 14 is a plan view showing the assembly of a decoiling means and a slitting means.
- Figure 15 is a sectional view of yet another type of tensioning device.
- Figure 16 is a sectional view thereof, taken along the line 16—16 in Figure 15.
- 35 Figure 17 is a semi-sectional view of the decoiling means exclusive of the drive, the sectional part taken along the line 17—17 of Fig. 14.
- Figure 18 is a section along the line 18—18 of Figure 17.
- 40 Figure 19 is a sectional view of a flange assembly.
- Figure 20 is a sectional view of a plug assembly.
- 45 In Figure 1 we have shown strip material 1 being decoiled by means of a decoiler indicated generally at 8. The decoiled strip passes to a slitting means indicated generally at 8. This means will be described more in detail hereinafter. It may be provided with a scrap chute 9, which is shown best in this figure and in Figure 11. It does not constitute an essential limitation on our inven-
- 50

tion, and will not be described otherwise than to point out that it is a means for conducting away any scrap trimmed from the strip stock, and may be employed to take the scrap to a baler.

The slotted strip which, as already indicated, may be a single edge-trimmed strip, or may have been severed into a plurality of narrow strips, is conducted to a tensioning device indicated generally at 11 in Figure 1. From this device it proceeds to a recoiling mechanism 14. This mechanism may, if desired, be provided with a flexible, removable, coiling sheath indicated generally at 15.

The slitting device 8 may be of available form, and may on a suitable base comprise upper and lower shafts 11a and 18a upon which may be mounted such mating cutting knives or discs 19 as may be desired for the particular trimming or slitting purpose. The slitter may be powered by a motor 20 through a suitable drive, not detailed. Such a slitter is usually provided with an entering knee roll 21 over which the strip passes, and an entering set of initial pinch rolls 22, 23. Intermediate the knee roll and the pinch rolls there may be suitable guide means. These, in the exemplary embodiment, may comprise sheave-like guide discs 24 (Fig. 14), mounted upon a suitable adjustable framework. A pair of exit pinch rolls 25, 26, are usually provided, and these may be powered as at 27 to assist in drawing the strip through the slitter.

The problem of keeping the strip properly tracked in the slitter cannot usually be solved by the bare provision of guide means 24. This is especially true when the strip is thin, so that its edges are likely to become damaged, and where the strip in the initial coil is not evenly wound. We have made provision not only for the accurate initial adjustment of the coil with respect to the slitting device, but also for the effecting of changes in this adjustment as may be required from time to time by variations in a single coil. To this end our decoiling device comprises a pair of flanges 27, 28, and tapered mandrel or plug portions 29 and 30, adapted to engage within the central opening of a coil of strip material to be decoiled. These elements are slidably mounted on a shaft 31, and their positions on this shaft may be varied individually by means of handwheels 32 and 32a for the flanges, and 33 and 33a for the mandrel portions. Thus, the mandrel portions 29 and 30 can be engaged within the central opening of a coil, and the flanges 27 can be brought against the ends of the coil.

It will also be clear that by manipulation of the several handwheels the position of the engaged coil with respect to some other element in space, such as the slitter, can be varied without varying the engagement of the coil.

The shaft 31 is severable, and one of its bearing supports 34, is mounted on ways 35 and can be withdrawn or advanced together with its portion of shaft 31 by means of a small motor 36 driving a threaded shaft 37 engaging within a base block on the bearing support, as most clearly shown in Fig. 18. This permits the placing of a coil initially over the shaft 31, or its removal therefrom if that should be desired. The bearing support 34 may be locked in final operating position by bolt means 141 engaging the base of the bearing support. The other bearing for the shaft 31 is indicated at 38; and the shaft is connected through a gearing 39 to a device 40. The device 40 may be a motor whereby the shaft 31 may be turned if desired, but such a motor will usually be

provided with additional field coils whereby it can act as a generator and impose a resistance to the rotation of the shaft 31 so as to tension the strip as it is being decoiled.

5 An exemplary construction of the decoiling means is illustrated in Figs. 17, 19 and 20. A short stub shaft 31a with a reduced end is journalled in the bearing support 34. The reduced end is withdrawable engageable in a roller-bearing or other anti-friction bearing means fixed in hollow or bore in the end of shaft 31.

The plug 30 is provided with a sleeve 143 affixed to it, and having one or more keys 144 adapted to engage in a keyway or keyways 144a of the shaft 31. The sleeve is also provided with an external keyway or keyways 145, and the free end is threaded as at 146 (Fig. 20). The hand wheel 33 has a threaded hub 147 which engages the threads on the shaft 31; and the hub has a connection with the sleeve 143 which will permit relative rotary motion while preventing relative longitudinal motion, such as that shown.

The construction of the opposite plug 29 and its associated parts may be the same. However here it is advantageous to connect the hub of the hand wheel 33a to the sleeve of the plug by means of a latch 148 (Fig. 17) engageable in an annular groove 149 on the sleeve.

The flange 28 (Fig. 19) is arranged to slide over the plug sleeve. To this end it also is provided with a sleeve, or at least a series of elongated members 150 of sufficient length to maintain the flange normal to the sleeve. The inner edges of these members form keys slidable in the keyways 145 of the plug sleeve.

40 The hub 151 of the hand wheel 32 is threaded so as to be engageable with the threads 146 on the plug sleeve 143. The hub has a connection with the flange 28 such as will permit relative rotary motion while preventing relative axial motion. As shown in Fig. 19, this may be accomplished by providing an annular projection on the hub, and a detachable means on the flange 28 which, with the flange, presents an annular groove within which the projection engages.

45 The skirt of the plug 30 may be notched at intervals as at 152 so as to provide intervening tongues, and these tongues pass through perforations 153 in the flange 28. The relationship is clearly shown in Fig. 17.

50 After the strip has been slit, it passes into the tensioning device 11 through the guides which have already been mentioned. The tensioning device is a means for gripping the slotted strip or strips in a very positive manner and in such fashion as to retard the movement of the strip with a carefully controlled force which may be maintained constant when the desired value has been achieved. The tensioning device is preferably of such character as to be self-threading.

55 It can be made in various modifications, but in general it comprises two or more rotatable cylinders or rolls about which the strip or strips pass in a curved path, and two or more flexible friction belts which engage the strip. In one modification the strip or strips directly contact the surfaces of the rolls and are held thereagainst by the belts. In other modifications both belts pass around the operative rolls, with the strip or strips engaged between the belts. The retarding force or forces which are productive of the tension, may be applied directly to the rolls or to the belts, or both.

60 We have discovered that if the slotted strip is 75 properly guided into the tensioning device, and

if the tensioning device maintains a constant tension, guiding between the tensioning device and the recoiler is not necessary, even in an instance where the original strip is slit apart into a large number of narrow strips, and where these narrow strips are formed into spaced, side-by-side coils on the same recoiler mandrel.

One form of the tensioning device is shown in Figure 2. Here the device has a pair of side frames 41 between which the rolls 42 and 43 are mounted on appropriate shafts. Another similar roll 44 is also mounted between the side frame members and acts in part as a return for a lower belt member 45 which passes about the peripheries of the rolls 42 and 43, and over a small sheave or roller 46. This last mentioned roller is mounted on a pair of arms, one of which is shown at 47, and which are pivoted as at 48 on the side frames. Link members 49 engage these arms, and the belt 45 may be tensioned by drawing these links forwardly by means of one or more eye-bolts 50 passing through a bracket 51 connecting the side frames of the machine, and provided with nuts 52.

The other belt 53 also passes about the periphery of the rolls 42 and 43, but does not pass about the periphery of the roll 44. It returns over a pair of small rolls 54 and 55. The first of these is mounted on a shaft between the side frames of the machine; but the roll 55 has its shaft mounted on arms 56. Links 57 are pivoted to these arms, and the belt 53 may be tensioned by drawing upwardly on these links by means of eye-bolts 58 passing through a bracket 59 and provided with adjusting nuts 60.

As shown in Figure 3, the shafts 42a and 43a of the corresponding main rolls, pass through bearings in the side frames of the device, and may be connected through gear boxes 61 and 62 to generators 63 and 64, whereby a retarding force is applied to them. We prefer the use of generators; but it is not beyond the spirit of our invention to utilize any other retarding means which can be adjusted and controlled. Thus, we may provide the shafts 42a and 43a with brake drums, and apply brakes to them.

It will be evident in Figure 2 that the slit strip 1a can be passed into the tensioning device between the belts 45 and 53. It is forced to follow these belts as they pass around the surfaces of the rolls 42, 43; so that the machine is self-threading. The strip or strips are tightly bound between the frictional surfaces of these belts, and the belts themselves are tightly bound to the surfaces of the rolls 42 and 43, one belt directly contacting the surface of each roll. Thus, the strip 1a will not slip with relation to the belts, nor will the belts slip with relation to the rolls. An even application of a restraining force to the rolls will result in an even tensioning of the strip between the tensioning device and the recoiler. Another form of tensioning device is shown in Figures 4, 5, and 6. In this form two rolls 65 and 66 are employed, mounted between side frames 67 and 68 of the machine. These rolls may be geared together as at 69, and may be connected through a gear box 70 to a generator 71 or other retarding means. In this form of the device each of the rolls has a separate belt arrangement. The belt 72 on the lower roll passes around sheaves or rolls 73, 74, and 75, which are mounted between arms 76 and 77. These arms in turn are affixed to a shaft 78 by which the entire belt arrangement may be approached to or drawn away from the roll 66. A crank or lever arm 79 is affixed to the shaft 78,

5 and is connected to the piston rod 80 of a fluid pressure cylinder 81. By means of this cylinder the belt arrangement may be moved from the position shown in Figure 5 to the position shown in Figure 6. Also, the action of the cylinder 81 will be to press the belt 72 very tightly against the surface of the cylinder 66 or against the slit strip as it passes over the surface of that cylinder. If desired, the belt roll 75 may be mounted slidably in a slot 82 on the arms 76 and 77, and the shaft may be urged in one direction in this slot by means of a compression spring 83 having adjustment means 84. When the belt device is in the position shown in Figure 5, fluid pressure in the cylinder 81 cannot over-tension the belt 72, as will be evident.

10 The upper belt 85 is provided with similar rolls 86, 87 and 88 (the latter of which rolls may have a spring means similar to that just described) mounted between arms 89 and 90. These arms are affixed to a shaft 91 having bearings in the side frames 87 and 88. An arm 92 is fixed to the shaft 91 and is connected by link 93 to another arm 94 affixed to the shaft 78 so that the same pressure cylinder arrangement 81 can operate both belt arrangements.

15 The belt arrangements may thus simultaneously be swung from the closed position shown in Figure 5 to the open position shown in Figure 6. The structure of Figures 4, 5, and 6 is not fully self-threading, but it is easy to thread when the belt arrangements are open as shown in Figure 6.

20 Yet another tensioning arrangement is shown in Figures 15 and 16. Here a pair of rolls 95, 96, are journaled on shafts maintained in fixed relation to each other by suitable machine frame elements. A lower belt 97 passes about the cylinder 95, then about the cylinder 96, upward diagonally about a small roll 98, and downwardly under a small roll 99. It returns around a small fixed roll 100. The shaft of the roll 99 is mounted in ways 101 in which its position may be adjusted by threaded rods or shafts 102 and nuts 103, whereby to adjust the tension of the belt.

25 The upper belt 104 passes downwardly about the periphery of the roll 96 and upwardly about the periphery of the roll 95, returning over upper small rolls 105 and 106, the latter of which may be provided with tension adjustment means similar to those heretofore described.

30 In this structure the shaft 95a may be connected through a gear box 107 to a generator or other braking means not shown. Similarly, the shaft of roll 98 can be braked if desired; but we have also shown the shaft of roll 105 connected through a gear box 108 to a generator 109 so that braking force is applied to the belt 104. In a similar fashion, a braking force could be applied to belt 97.

35 We employ guide means in connection with our tensioning devices, and on the entering side thereof. These guide means are indicated generally at 110 in Figures 1, 5, 6, 11, and 15. Various kinds of guide means may be employed. The type which we prefer, but to which our invention in its broadest aspect is not limited, is illustrated in Figures 7 to 10 inclusive. This guide means is especially suitable for the guiding of thin strips without damaging the edges thereof, where the materials are properly tracked by structures and adjustment features such as those herein described. In form, our preferred guide means is an endless travelling chain comprising links 111 and 112 connected by rivets or pins 113 which pass through rollers 114. In each guide means the endless chain passes about the periphery of an elongated metal

piece 115 with rounded ends, and the small rollers 114 roll on the edge surfaces of this piece. The piece is supported at the proper height above a base 116 by block means 117. The base has an upwardly extending lip 118 at one side, upon which the edge of the strip material 1a may rest, and which will maintain the edge of the strip material at the proper height to be contacted by the rollers 114. In order to hold the strip material down onto the lip 118, we may provide a hold-down 119 supported by a bracket 120, which in turn is mounted on a block 121 on the metal piece 115.

Where the strip material is merely to be edge trimmed, it may be necessary only to provide two of these guiding devices at the entering side of the tension means, as we have shown in Figure 7. Here the bases 116 and 116a of a pair of the guiding means are slidably mounted upon a bar 122 or other means providing ways. The sidewise position of the guides may be adjusted by means of threaded shafts 123 and 124 rotatably mounted in brackets 125, 126, on the tensioning machine frame. The shafts 123 and 124 are not longitudinally movable. Threaded portions of them engage in threaded bosses 127 (see Fig. 9) which are attached to or form part of the base 116 of each guide means.

Where the initial strip is slit into a plurality of narrow strips, it is necessary to provide side guides for each such strip. Also, because there is not sufficient space for the guide means between the side edges of adjacent strips as they are slit from the main strip, it is necessary to carry alternate ones of the narrow strips out of the general path of the rest, and provide guide means for the strips before they rejoin each other in the same path. Thus, in Figures 12 and 13 we have shown alternate ones 1b of the narrow strips depressed and passing beneath a deflecting roll 128. In these figures the strips 1a in the upper path are provided with guide means indicated generally at 129, while the strips 1b in the lower path are provided with guide means 130. The various guide means are adjusted not only to keep the several narrow strips in track, but also to maintain a desired spacing between them as they enter the tensioning device.

The final take-up or recoiling mechanism will generally comprise a shaft 131, upon which will usually be mounted an expandable mandrel 132. The shaft is of course journaled in a machine frame, and will be connected, through a gear box 133, to a motor or the like 134, to provide the necessary coiling power. The precise nature of the mandrel 132 does not form a necessary limitation on our invention, and the recoiling means itself may likewise be considerably varied without departing from the principles set forth herein. Thus, we may, if desired, provide the coiling bridle or sheath hereinabove referred to and indicated in Figure 1 at 15. This comprises a carriage 135 slideable on ways 136, and bearing interspaced frames 137. These frames also bear linked arms 138 and 139; and a belt 140 passes around various rolls journaled between the arms. When the carriage 135 is moved to the left in Figure 1, the belt 140 can be caused to surround the mandrel 132 under tension, the arms 138 and 139 swinging slightly to permit this. A suitable tensioning device of hydraulic or other character, is provided, but has not been detailed in the drawings of this case. When a slit strip or strips is introduced between the mandrel and the

belt 140, the belt 140 will bind it tightly to the surface of the mandrel, and as the mandrel is rotated by the motor 134, the strip or strips will be coiled thereon. As the coiling progresses and the coils grow in diameter, the portion of the belt 140 surrounding the mandrel moves to accommodate this growth while still holding each succeeding convolution tightly to the surface of the coil. When the coil is complete, it may be bound in any suitable fashion, and the entire coiling bridle moved out of the way as shown in Figure 1. Then the mandrel 132 can be collapsed and the coil or coils withdrawn therefrom.

We have found that using the mechanism hereinabove described, even with very thin, brittle strip metal, not characterized by flatness, we can produce tight, even coils wound under exactly controlled tension. Such coils are suitable for annealing as well as for handling and shipment. Where the initial strip material is a material such as the welded silicon steel strip hereinabove described, and where it is merely to be edge trimmed and rewound into a single large coil, we have found it advantageous somewhat to crown the center of the mandrel 132. But we have also found that where the initial strip material is slit apart into a plurality of narrow strips, it is possible to form individual coils of these strips, which coils are uniform in contour and uniformly wound in spaced relationship on a single mandrel, and without the use of intermediate spacing flanges. So far as we are aware, this has not been accomplished before. It is accomplished in our apparatus by the method of carefully tracking the materials throughout the various instrumentalities, and by rendering the recoiling tension to all intents and purposes independent of variations of tension such as are bound to occur during decoiling and slitting. It is also dependent in very large measure on the maintenance of very carefully controlled and uniform tension conditions during recoiling; but a very great commercial advantage of our invention lies in the fact that if the materials are guided as they enter the tensioning means (at which time they are under little or no tension and can readily be guided without edge damage), and if the tensioning means are such as shown in these specifications and drawings, it is not necessary to apply guides to the strip or strips between the tensioning means and the recoiler, or at any other time when the strip or strips are under heavy tension. Thus, not only are the difficulties of guiding overcome, but the likelihood of damage to the strip edges is substantially eliminated.

Modifications may be made in our invention without departing from the spirit of it. Having thus described our invention, what we claim as new, and desire to secure by Letters Patent is:

1. A process of decoiling, slitting and recoiling strip metal, which comprises decoiling the metal strip while maintaining the side edges thereof accurately adjusted to the receiving position of a slitter, slitting the metal under conditions in which the metal is tensioned as it approaches the slitter and untensioned after it leaves the slitter, thereafter guiding the metal into a rotary tensioning device and passing it directly from said tensioning device into a recoiling means, the said tensioning device being arranged to exert a retarding force on the movement of the material, and the said recoiling means being a powered device, whereby the tension on the material during recoiling is maintained substan-

tially constant in spite of variations in tension occurring elsewhere in the system.

2. The process claimed in claim 1, including the steps of applying power to the slitting device and applying a retarding force to the decoiler.

3. The process claimed in claim 1, including the steps of applying power to the slitting device and applying a retarding force to the decoiler, and in which the said strip is severed into a plurality of narrower strips, said narrower strips being simultaneously wound on a single mandrel in said recoiling device in side by side relationship, and without the use of spacing means between the said coils.

4. A process of decoiling, slitting and recoiling thin strip metal, which comprises decoiling said metal from a coil, and laterally adjusting the path of travel of said decoiled metal with reference to a slitting means by adjusting the position of the coil with reference thereto, guiding said metal into said slitting means, causing said metal to move through said slitting means under power, whereby said metal is substantially untensioned beyond said slitting means, and while said metal is so untensioned, guiding it into a rotary tensioning device and thence to a recoiler, said tensioning device acting to retard the movement of said metal, and said recoiling device being a powered device.

5. The process claimed in claim 4, in which said metal is slit at said slitter into a plurality of narrow strips, and in which said strips are caused to follow paths beyond said slitter, which paths are displaced as respects each other, guiding said strips while so displaced, and thereafter causing said displaced paths to merge as said strips enter said tensioning device.

6. In combination, a decoiling means, a slitter, a tensioning device and a recoiler, in the order named, said slitter being a powered device whereby to cause strip material to move through it under power, leaving it substantially untensioned therebeyond, and said tensioning means being arranged to apply a retarding force to said material, said recoiling means being a powered device.

7. In combination, a decoiling means, a slitter, a tensioning device and a recoiler, in the order named, said slitter being a powered device whereby to cause strip material to move through it under power, leaving it substantially untensioned therebeyond, and said tensioning means being arranged to apply a retarding force to said material, said recoiling means being a powered device, and guide means located between said slitter and said tensioning means and arranged to

guide said material while said material is substantially untensioned.

8. In combination, a decoiling means, a slitter, a tensioning device and a recoiler, in the order named, said slitter being a powered device whereby to cause strip material to move through it under power, leaving it substantially untensioned therebeyond, and said tensioning means being arranged to apply a retarding force to said material, said recoiling means being a powered device, and guide means located between said slitter and said tensioning means and arranged to guide said material while said material is substantially untensioned, said tensioning means comprising spaced rollers, and belts adapted to cause said material tightly to engage the surfaces of said rollers, and means for applying a retarding force to said rollers.

9. In combination, a decoiling means, a slitter, a tensioning device and a recoiler, in the order named, said slitter being a powered device whereby to cause strip material to move through it under power, leaving it substantially untensioned therebeyond, and said tensioning means being arranged to apply a retarding force to said material, said recoiling means being a powered device, and guide means located between said slitter and said tensioning means and arranged to guide said material while said material is substantially untensioned, said tensioning device comprising spaced rolls, belts following a sinuous path about the peripheries of both rolls, said belts defining the path of travel of said material through said tensioning means, means for tensioning said belts, and means for applying a retarding force to said rolls.

10. In combination, a decoiling means, a slitter, a tensioning device and a recoiler, in the order named, said slitter being a powered device whereby to cause strip material to move through it under power, leaving it substantially untensioned therebeyond, and said tensioning means being arranged to apply a retarding force to said material, said recoiling means being a powered device, and guide means located between said slitter and said tensioning means and arranged to guide said material while said material is substantially untensioned, said tensioning device comprising spaced rolls, belts following a sinuous path about the peripheries of both rolls, said belts defining the path of travel of said material through said tensioning means, means for tensioning said belts, and means for applying a retarding force to one at least of said belts.
